UNITED STATES PATENT OFFICE.

JULES AUGUSTIN BON, OF VINCENNES, FRANCE.

PROJECTILE.

No. 879,079.

Specification of Letters Patent.

Patented Feb. 11, 1908.

Application filed December 26, 1906. Serial No. 349,432.

To all whom it may concern:

Be it known that I, JULES AUGUSTIN BON, of Pavillon 10, Vieux Fort, Vincennes, Seine, Republic of France, lieutenant colonel in the 5 Twelfth Regiment of Artillery, have invented Improvements in Projectiles, of which the following is a full, clear, and exact description.

The present invention relates to an elongated projectile which, by its construction 10 and during its movement in the air, has its longitudinal axis always brought to the tangent to the trajectory of its center of gravity, on which it takes a position of stable equilibrium, without its being necessary to impart 15 to the projectile a rotary motion about this longitudinal axis. This projectile may be fired in a smooth bore gun or ordnance, or employed for loading a shell, a case shot canister or a sporting or other cartridge.

20 This invention will be hereinafter described with reference to the accompanying drawing, in which;

Figure 1 shows in elevation a first form of construction of the improved projectile. 25 Fig. 2 is a plan thereof. Fig. 3 is an under side view. Fig. 4 is a transverse section on the line D—D of Fig. 1. Fig. 5 shows in elevation a second form of construction of my improved projectile. Fig. 6 is a plan thereof. 30 Fig. 7 is an under side view. Fig. 8 is a transverse section on the line E—E of Fig. 5.

My improved projectile comprises: 1. A solid head very elongated and with a very sharp point, forming the projectile proper. 35 2. A directing piece rigidly fixed to the rear part of the head to form a kind of rudder always directing the common axis into the direction of the motion.

In the first form of construction shown in 40 the drawing, Figs. 1 to 4, the head A is cylindrical; it is surmounted by an ogival point and terminated in the rear by the directing piece B having four branches, formed by four plates or bearings very thin crossing 45 each other upon the axis of the projectile.

In the second form of construction shown in the drawing Figs. 5 to 8, the head A' has the form of a prism with a hexagonal base; it

is surmounted by a pyramidal point and is terminated in the rear by a directing piece 50 B' with three branches or ribs. The grooves formed by the branches or ribs of the directing pieces have their inner ends inclined to correspond with the incline of the points or heads.

The head of the projectile may be of square section with pyramidal point; in that case the directing piece, will be the four branches. The prism with hexagonal or square bases give a minimum lost space in the case of a 60 packing or stacking together in the interior of a shell, or of a case-shot canister, or a cartridge; the directing piece should be light; it is necessary and sufficient if it directs the head and assists the initial pressure 65 or impact of the gases. It is fitted to the head by an incline of the same form as the point, but hollows.

The forms, details, bore, total heights and the height of each constituent part of this 70 projectile may obviously be varied without in any way departing from the nature of the invention.

I claim

1. A projectile, comprising a head having 75 a pointed end, and a directing piece or tail of the same diameter as the head and having longitudinal grooves forming a plurality of ribs, the walls of the grooves at their inner ends being inclined to correspond with the 80 incline of the point of the head.

2. A projectile, comprising a head hexagonal in cross section with a pyramidal point, and a directing piece or tail of the same diameter as the head and provided 85 with grooves forming three ribs, the walls of the grooves at their inner ends being inclined to correspond with the incline of the point of the head.

The foregoing specification of my improvements in projectiles signed by me this eleventh day of December, 1906.

JULES AUGUSTIN BON.
